TIE LOCK

Norman C. Hampton, Portland, Oreg.

Application December 27, 1935, Serial No. 56,327

6 Claims. (Cl. 24—56)

This invention relates generally to supports for neckties and particularly to a support for holding the tie in its proper position when tied.

The main object of this invention is the production of an exceedingly simple and efficient form of tie lock which will be simple to construct and easy to apply to a collar button for the purpose of supporting the tie knot thereon.

The second object is to so construct the device that the tie knot will be held against lateral shifting as well as vertical shifting without in any way injuring the tie or collar.

The third object is to so construct the device that although the collar button itself is used as a support, the means for attaching the device to the button extends well above the level at which the knot is being supported.

I accomplish these objects in the manner set forth in the following specification as illustrated in the accompanying drawing, in which;

Fig. 1 is a front elevation of the device.

Fig. 2 is a side elevation of the device.

Fig. 3 is a plan.

Fig. 4 is a front elevation showing a collar with a tie attached and the position occupied by the device with relation thereto.

Fig. 5 is a vertical section taken along the line 5—5 in Fig. 4.

Similar numbers of reference refer to similar parts throughout the several views.

Referring in detail to the drawing, there is shown a common form of necktie 10 whose portion 11 passes around the collar 12 and then forms the knot 13.

Referring particularly to my device, same will be seen to consist of a flat body 14 in which is formed a vertical slot 15 extending from the bottom edge 16 almost to the top edge 17. Extending forwardly from the body 14 is a curved ledge 18 whose intermediate portion is bent downwardly toward the edge 16 for the purpose of forming a saddle on its top side for the tie knot 13. An opening 19 is formed in the ledge 18 to supply the material for the downwardly extending ends 20 which form a fork between which the slot 15 receives the collar button 21.

The operation of the device is as follows:

The collar is secured in the usual manner by means of the collar button 21. The tie is then secured in the customary manner and the device is then applied by simply placing it downwardly behind the head of the button 21 until it reaches the position shown in Fig. 5. The tie knot 13 is then permitted to rest in the saddle formed by the curved ledge 18. Obviously, the tie knot 13 which is supported on the ledge 18 not only is held against a downward movement, but its upper end is urged in an upward direction due to the fact that the ledge 18 forms a fulcrum about which the knot is moved by the

weight of the tie 10 itself. It therefore follows that the upper end 22 of the tie knot 13 is always close to the upper edge 23 of the collar 12 presenting a very neat appearance. Also, the lower end 24 of the tie knot 13 is held central between the wings 25 of the collar 12.

While in the ordinary production of this device a suitable sheet metal is preferable, the same results are obtainable by the use of wire or composition materials.

It is not my intention to be limited to the precise form illustrated in the drawing, but I intend to cover all forms and modifications of the invention which fall fairly within the appended claims.

1. A tie lock consisting of a forked member adapted to be hung from a collar button and having a tie knot support extending forwardly therefrom below said button and above the lower open ends of the fork.

2. A tie lock consisting of a forked member adapted to be placed downwardly over a collar button and having a forwardly projecting saddle formed thereon disposed below the junction of said forked member and button adapted to support a tie knot, said saddle curved upwardly on its top side in transverse directions.

3. A tie lock consisting of a forked member adapted to be inserted downwardly over a collar button and having a curved saddle formed in front of said forked member below the upper end of the button engaging fork upon which a tie knot can rest, the middle of said saddle being lowermost.

4. A tie lock consisting of a forked member adapted to be inserted downwardly over a front collar button and having extending forwardly from the sides of said fork between the upper and lower ends thereof means for supporting a tie knot consisting of an arcuate saddle, the sides of which are higher than its intermediate portion.

5. A tie lock consisting of an upright forked member adapted to be inserted downwardly over a front collar button and having extending across the front of said forked members above the lower ends thereof a tie supporting saddle curved upwardly in a transverse direction.

6. A tie lock consisting of a T-shaped member of sheet material, the stem of said T-shaped member being transversely curved and the cross member of said T-shaped member being slotted from one end thereof to receive a collar button, said slot extending from the end of said cross member past its junction with said stem, said stem being cut away at its pointed junction with said cross member to provide clearance for the collar button and to furnish material for the open side of said forked cross member portion.
